UNITED STATES PATENT OFFICE.

CARL S. HANAU, DECEASED, LATE OF NEW YORK, N. Y., BY DOROTHY G. HANAU,
EXECUTRIX, OF NEW YORK, N. Y.

TABLE-ELEVATING DEVICE FOR PAPER-FEEDING MACHINES.

1,334,367.

Specification of Letters Patent. Patented Mar. 23, 1920.

Application filed May 20, 1919. Serial No. 298,464.

To all whom it may concern:

Be it known that CARL S. HANAU, deceased, late of the city of New York, in the county of Bronx and State of New York, has invented certain new and useful Improvements in Table-Elevating Devices for Paper-Feeding Machines, of which the following is a specification.

The present invention relates to table-elevating devices for paper feeding machines, and more particularly to a device adapted especially for use in connection with a paper feeding machine of the type described in application for U. S. Letters Patent, Serial No. 235,412, filed by the said Carl S. Hanau on May 18, 1918.

In the said application, a machine for feeding sheets of paper from a stack is described, including a feeding roller having a bodily motion to and from the front edges of the sheets and adapted to engage the top sheet of the stack or pile. The stack of paper sheets is supported in machines of this type by a table, that is usually provided with automatic means for elevating the same, the elevating means being controlled by the height of the pile, the object being to maintain the level of the top sheet substantially uniform.

The main object of the present invention is to provide a table-raising mechanism that is controlled by the feeding devices of the sheets, in contradistinction to mechanisms heretofore in use, wherein separate controlling members are provided, with the result that not only are the machines complicated in construction, but are caused to operate the elevating means too slowly.

Another object of the invention is to so construct the elevating means that it can be conveniently mounted upon machines already in use, without necessitating material changes in the construction of the latter.

With these and other objects in view, which will more fully appear as the nature of the invention is better understood, the same consists in the combination, arrangement and construction of parts hereinafter described, pointed out in the appended claim and illustrated in the accompanying drawings, it being understood that many changes may be made in the size and proportion of the several parts and details of construction within the scope of the appended claim

without departing from the spirit or sacrificing any of the advantages of the invention.

One of the many possible embodiments of the invention is illustrated in the accompanying drawings, in which:

Figure 1 is a side elevation of a portion of a sheet feeding machine having the improved table raising attachment mounted thereon; Fig. 2 is a front elevation thereof; and Fig. 3 is a view, similar to the one shown in Fig. 1, with the elements in other positions.

In the drawings, the numeral 10 indicates one of the side frame members of the machine, of which there are two, one on each side of the machine, said frame members being connected in any suitable manner, for instance by tie rods, not shown. The stack of paper, denoted by the numeral 11, is carried by a table 12, which is supported by members 13 adjacent the inner sides of the frame members 10, said supporting members being each provided with a lug 14, extending through a slot 15 in the respective side frame member. Each lug has a screw-threaded bore, in mesh with a screw-threaded spindle 16. These spindles are each provided at their upper ends with a bevel gear 17, in mesh with a similar gear 18, the gears 18 being fixed to a shaft 19, that is rotatably mounted in the side frames 10. This shaft is intermittently rotated in the proper direction by a mechanism hereinafter to be described, for the purpose of raising the table, as the stack of paper thereon decreases in height.

The paper stack is guided in its upward movement by a transverse frame 20, having at its upper end a forwardly bent inclined lip 21.

The feeding and separating means comprises a suitable number of rollers 22, each attached to a spindle 23, which is rotatably journaled in a forked lever 24. These levers are fixed each to a rock-shaft 25, which is slidably arranged in horizontal guides (not shown), a mechanism being provided for causing the said shaft to move back and forth in its guides and also to rock the same, as appears from the application for Letters Patent above referred to. This mechanism serves to cause the rollers 22 to engage the top sheet when the said rock-shaft starts its forward movement, and to disengage the

same from the pile when the rock-shaft starts its backward movement.

To the rock-shaft 25 is furthermore fixed a rearwardly extending arm 26, coöperating with a detent 27, in the form of a lever, that is fulcrumed at 29 to one of the side frame members 10. The free end of this detent is provided with a lug 30, adapted to coöperate with a series of ratchet teeth 31 on an arc-shaped member 32, the latter being fixed to a sleeve 33, that is oscillatably mounted upon the shaft 19. On this sleeve is provided an upwardly extending arm 34, to which is pivoted at 35 a pawl 36, that is held, preferably, by gravity in engagement with the teeth of a ratchet wheel 37, the latter being keyed to the shaft 19. The teeth 31 on the arc-shaped member 32 are disposed eccentrically in relation to the axis of the shaft 19 to mesh with the lug 30 on the detent 27. The sleeve 33 and the parts carried thereby are so disposed and weighted that, when released by the detent 27, gravity causes the mechanism to move around the axis of the shaft 19, in the direction of the arrow shown in Fig. 1 of the drawings.

The arc-shaped member 32 is provided with a projection 38, with which coöperates a slide 39, that extends through a guide 40. The lower end of the slide is pivoted at 41 to a lever 42, the latter being fulcrumed at 43 to one of the side frame members 10. This lever carries an anti-friction roller 44, bearing against a cam 45, that is fixed to a rotary shaft 46, the latter being driven from the main shaft of the machine, making one revolution during each cycle of operation of the feeding rollers 22.

The operation of the table-raising mechanism is as follows:—If the height of the stack of paper on the table is below normal, the arm 26 rises and disengages the lug 30 of the detent 27 from the ratchet teeth 31 of the arc-shaped member 32 when, during the separating and feeding operation, the rollers 22 come into contact with the top sheet. Gravity then causes the sleeve 33 and the parts carried thereby to swing around the axis of the shaft 19 in the direction of the arrow shown in Fig. 1 of the drawings, as far as the detent 27 will permit such movement. The pawl 36 is thus brought into engagement with a tooth of the ratchet wheel 37 in rear of the tooth with which it

was previously engaged (Fig. 3). As now 55 the cam 45 rotates, it causes, by the intermediary of the lever 42, the slide 39 to move in the direction of the arrow shown in Fig. 3 of the drawings, thereby turning the ratchet wheel 37, which, in turn, through 60 the bevel gears 17 and 18, gives a partial turn to the screw-threaded spindles 16, with the result that the table is elevated.

It is to be observed that the extent of movement of the detent 27 depends entirely 65 upon the height of the stack of paper on the table, the movement of the outer end of the arm 26 being dependent upon the position of the feeding rollers 22 when in contact with the stack during the separating 70 and feeding operations. On the other hand, the level, to which the projection 38 on the arc-shaped member 32 is allowed to sink, depends entirely upon the position of the lug 30 on the detent 27. Consequently the 75 extent of the upward movement of the table 12 is controlled at any time by the height of the paper stack.

What is claimed is:—

In a paper feeding machine, the combination with a frame, of a stack-carrying table slidably mounted thereon, a rock-shaft on said frame, sheet feeding means carried by said shaft, an arm fixed to said shaft, a second shaft rotatably mounted on said frame, 80 screw-threaded spindles in engagement with said table, a driving connection between said second shaft and said spindles, a ratchet wheel fixed to said second-named shaft, a pawl-carrying arm loosely mounted upon 85 said second-named shaft having an arc-shaped toothed extension below said last-named shaft, said pawl carrying member being caused to swing by gravity around its shaft, a detent pivoted to said frame 90 having a lug adapted to mesh with the teeth of said arc-shaped member positioned to be actuated by said arm, and a slide operating in unison with said feeding means for returning said pawl-carrying member to normal position from its gravity-induced position.

Signed at New York, in the county of New York and State of New York, this 7th day of May, A. D. 1919.

DOROTHY G. HANAU,
*Executrix of the last will and testament of
Carl S. Hanau, deceased.*
